UNITED STATES PATENT OFFICE.

DANIEL B. LUTEN, OF INDIANAPOLIS, INDIANA.

DESIGN FOR A RAILING-BLOCK.

40,667.

Specification for Design.

Patented Apr. 26, 1910.

Application filed February 16, 1909. Serial No. 478,341. Term of patent 14 years.

To all whom it may concern:

Be it known that I, DANIEL B. LUTEN, a citizen of the United States, residing at Indianapolis, in the county of Marion and State of Indiana, have invented a certain new, original, and ornamental Design for Railing-Blocks, of which the following is a specification.

The accompanying drawing is a perspective view of a railing-block embodying my design.

It will be seen from the drawing that the block comprises a base 1 of desired thickness, length and height and this base is surmounted by a vertical plate 2 having plain

side faces in which, at desired intervals there are formed ornamental figures 3 outlined within the body of the portion 2. The top corners of the base 1 are cut away at 4.

In use a plurality of these blocks are arranged end to end across the top of a bridge at its sides in order to produce a balustrade or hand rail.

I claim as my invention—

The ornamental design for a railing block as shown and described.

DANIEL B. LUTEN. [L.S.]
